GROUND VASE

Axel S. Carlson, New York, N. Y.

Application June 23, 1949, Serial No. 100,918

4 Claims. (Cl. 47—41)

1

This invention relates to ground urns or vases for use in memorials, cemeteries and similar places, and constitutes an improvement over my U. S. Patent No. 2,438,802, entitled "Ground Vase," issued on March 30, 1948.

An object of the invention is to provide a simple, efficient, durable device which can be inserted in the ground in a suitable ground chamber and can be used to receive flowers and the like, on such occasions as call for memorializing the departed, and which can be removed for the purpose of replenishing the water therein and for cleaning, but which is so related and tied to its receiving chamber that it can not be separated therefrom or stolen.

A further object is to provide an article of the class described, which is simple in operation so that anyone may operate it without any particular experience after the first operation.

A still further object is to provide a device which can be covered when not in use and in which the cover is related to the urn in such manner, that it can not be readily removed and can not be disturbed when the plot around the urn is being mowed by a lawn mower.

In brief and general terms, the invention includes a well for a ground urn, in which well is fixedly disposed a metallic shell to which a ground cap is permanently attached. The ground cap is substantially flushed with the ground and is preferably cup-shaped and provided with recesses to receive protruding ears on the upper outer surface of an urn or vase, which depends into the well from the ground cap or plate. The top of the device is covered by a cover or lid having a dependent curved finger to engage a socket on the inner wall of the urn, and having at its opposite side a cam shaped lug to engage with an opposite recess to jam the lid in position.

In order to prevent the lid and the urn from being permanently removed from the well, I provide a chain attached at one end to the under face of the lid adapted to pass through an opening in the flange on the ground plate, the other end of the chain being attached to the outer face of the urn preferably to the bottom thereof so that, while the lid and the urn may be removed in order to fill the urn with water, it is impossible, as long as the chain is unbroken, to permanently remove the lid and the urn from the well.

Further and more specific objects, features, and advantages will more clearly appear from a consideration of the detailed specification herein-after set forth especially when taken in connection with the accompanying drawings which illus-

2

trate a present preferred form which the invention may assume and which form part of the specification.

The preferred form of the invention is shown 5 in the drawings, of which:

Fig. 1 is a vertical cross section through the device showing on the right, in dotted lines, the lid and the urn removed from the well;

Fig. 2 is a plan view of the device;

10 Fig. 3 is an inverted section taken on the line 3—3 of Fig. 1;

Fig. 4 is a partial detail view of the connection of the locking chain with the lid; and,

15 Fig. 5 is a partial detail section showing the manner in which the locking chain passes through an opening in a flange of the ground plate.

Specifically as shown, the invention concerns the provision of preferably a concrete well 10 in the ground. This well is lined with a metal shell 11 which is placed first in the ground and then the concrete is poured in around it to effect a tight intimate junction between the two elements. The top of the shell or lining 11 is covered by a ground plate 12, which has an outwardly 20 extending peripheral flange 13 at the top, which extends outwardly over and beyond the top of the shell 11 to rest on the surface of the ground adjacent the top of the shell 11 as shown. The ground plate 12 is provided with a circular vertical inner wall 14 which lies closely adjacent the upper inner wall of the shell 11. At its bottom, this wall 14 is provided with an inwardly extending ring-like flange 15, the inner opening of which is sufficient to permit the reception therewithin of the ground urn or flower vase 16. Along the peripheral upper outer wall of the urn or vase, it is provided with outwardly extending ears 17 which are adapted to be seated in similarly shaped seats or recesses 18 formed on the upper surface of the flange 15 of the ground plate 12. These ears and recesses may be slightly different shape so that the urn may be seated on the ground plate flange 15 in a predetermined manner only. The top wall of the urn or vase 16 is 30 disposed and dimensioned to lie normally flush or level with the top of the ground plate 12 as shown in Figure 1.

Adapted to be disposed over the top of the urn or vase 16 is a lid or cover plate 19, which has a 35 slightly convexly curved top wall and over the top of the ground plate 12 and slightly beyond the diameter of the ears 17 to rest on the top of the ground plate 12 snugly. The cover has adjacent its peripheral edge, a dependent outwardly extending finger 20 adapted to be en-

gaged with a socket formed by the reversely curved wall 21 at the top of the ears 17, to hold the plate in position. Diametrically opposite this finger 20, is a dependent lug 22 adapted to extend down against an adjacent wall of the corresponding ear formed on the urn and provided with a slightly curved cam shaped front wall 23, which will jam the lug into position to hold the lid 19 in place. The lid on this side of it adjacent the cam lug 22, has a slightly elevated extending finger 24 to enable the lid to be lifted by the insertion of a tool beneath the finger to pry the lid loose. Otherwise, it is seen that the lid is only slightly elevated past the top of the ground plate so that it is not an obstruction to anyone walking over the ground, and it does not interfere with the operation of the lawn mowers over the surrounding grassy surface.

In order to provide simple means whereby neither the lid nor the urn can be permanently removed or stolen, I have provided a chain 24' which at one end is connected to a projection 25 on the outside of the urn near the bottom thereof. This chain passes up through an opening 26 in the flange 15 as shown in Figure 5, and the other end of it is connected as shown in Figure 4, to the underside of lid 19 at the point 27.

The ground plate 12 along the bottom of the flange 13 thereon, is provided with a series of dependent straps 28, which are suitably riveted as at 19 to the shell 11. In the operation of the device, the ground plate is by means of straps 28, riveted in permanent position with respect to the shell 11, and this unit is then placed in a hole in the ground with the under-surface of the flange 13 in line with the ground level. Concrete is then poured in around the shell and filled in until the proper level is reached beneath the flange 13. After this is set, a very permanent connection is thereby afforded between the shell 11 and the enclosing concrete well.

When one visits the plot for the purpose of placing flowers in the urn 16, the lid 19 is pried loose under the finger 24. By lifting on the finger 24, the finger 20 can be removed from its socket and the cap lifted up. With this removed, the urn can be lifted up out of the shell for the purpose of cleaning and/or filling it with fresh water to receive flowers after which, it may be replaced on the ground plate. It is obvious that the device is extremely simple, strong, durable, compact, and of few simple parts, and that the cover and the urn are so connected to each other and the ground plate that they can not be removed from the spot without raising the chain.

While the invention has been described in detail and with respect to the preferred form shown in the drawings, it is not to be limited to such details and forms since many changes and modifications may be made in the invention without departing from the spirit and scope of the invention in its broadest aspects. Hence, it is intended to cover any and all forms and modifications of the invention which may come within the language or scope of any one or more of the appended claims.

What I claim as my invention is:

1. A ground urn apparatus which comprises a well to receive an urn, a flanged ground plate disposed on the ground at the top of the well and having an aperture in the flange thereof, a cover detachably disposed on top of the plate, said cover having a slightly elevated horizontally extending finger, an urn suspended in the well on the ground plate, a socket on the urn, a dependent lug on the

cover and having a cam-shaped edge to engage with a wall of said socket to frictionally lock the cover to the urn, and a chain connected at one end to the cover and at the other end to the urn and passing through said aperture.

5 2. A ground urn apparatus which comprises a well to receive an urn, a flanged ground plate disposed on the ground at the top of the well, a metal shell forming a lining for the well and fixed to the ground plate, said ground plate flange having an aperture therein, a cover detachably disposed on top of the ground plate, said cover having a slightly elevated horizontally extending finger, an urn suspended in the well on the ground plate, 10 a socket on the urn, a dependent lug on the cover and having a cam-shaped edge to engage with a wall of said socket to frictionally lock the cover to the urn, and a chain connected at one end to the cover and at the other end to the urn and passing through said aperture.

15 3. A ground urn apparatus which comprises a well to receive an urn, a ground plate disposed on the ground at the top of the well, a shell lining the well, fingers on the ground plate dependent therefrom and connected to the shell, the ground plate having a cup-shaped recess, the bottom of which is formed by an inwardly projecting ring-like flange having an aperture therein, a plurality of seats on the upper surface of the flange, an urn having projecting ears at its upper end adapted to rest in said seats, a cover disposed on top of the ground plate, a dependent finger on the cover, 20 said urn having a socket to receive said finger, a second socket on the urn opposite the first mentioned socket, and a dependent lug on the cover and having a cam-shaped edge to engage with a wall of said second socket to frictionally lock the cover to the urn.

25 4. A ground urn apparatus which comprises a well to receive an urn, a ground plate disposed on the ground at the top of the well, a shell lining the well, fingers on the ground plate dependent therefrom and connected to the shell, the ground plate having a cup-shaped recess, the bottom of which is formed by an inwardly projecting ring-like flange having an aperture therein, a plurality of seats on the upper surface of the flange, an urn having projecting ears at its upper end adapted to rest in said seats, a cover disposed on top of the ground plate, a dependent finger on the cover, 30 said urn having a socket to receive said finger, a second socket on the urn opposite the first mentioned socket, and a dependent lug on the cover and having a cam-shaped edge to engage with a wall of said second socket to frictionally lock the cover to the urn, and a chain connected to the under side of the cover and passing through the aperture in said ground plate flange, the other end of the chain connected to the outside of the urn adjacent the bottom thereon within the well.
